D11-150.

OR D12,083 EX

Design No. 12,083, dated January 4, 1881.

UNITED STATES PATENT OFFICE.

CHARLES DOWLER, OF PROVIDENCE, RHODE ISLAND.

DESIGN FOR A FLOWER-POT.

SPECIFICATION forming part of Design No. 12,083, dated January 4, 1881.

Application filed November 12, 1880. Term of patent 3½ years.

To all whom it may concern:

Be it known that I, CHARLES DOWLER, of Providence, in the county of Providence and State of Rhode Island, have invented and produced a new and original Design for Flower-Pots with Saucers, of which the following is a full, clear, and exact description, reference being had to the accompanying photographic illustration, making part of this specification.

10 My invention consists in a design for ornamenting flower-pots with saucers, and used as an ornament for tables, hanging brackets, &c.

In the photograph, *a* represents the shell or body of a flower-pot of the usual inverted-frustum form. The top is ornamented by the geometrical scalloped band *b*, followed by a simple plain band, *c*. Near the center of the shell is formed another plain raised band, *d*. Resting upon this band are twelve contiguous 15 Grecian shells, *e*, while just below said band *d* are six sunken panels, *f*, of shield form, ornamented with four parallel horizontal bars, *g*. Alternating with said panels *f* are six other 20 similar panels, *h*, filled with the conventional clover-leaf, thereby producing a striking contrast. Between the upper and center bands

are formed the two medallions *i*, and also the ten series of incised work *k*, consisting of a ball and scroll. The bottom of the shell is ornamented by the plain incised band *l* and 30 series of short vertical lines with terminals *m*. The flower-pot rests upon the circular ornamental saucer *n*, supported by four feet, *o*, which terminate in a scroll, *p*, upon each side. The border of said saucer *n* is ornamented by 35 a series of partial rosettes, *r*, interlaced by two crossed bands.

Suitable colors may be employed to produce a more striking effect.

What I claim as my invention is—

40 A design for a flower-pot with saucer, in which the ornamentation consists of the bands *b c d*, Grecian shells *e*, panels *f* and *h*, medallions *i*, the series of incised work *k*, *l*, and *m*, the saucer ornamented by the feet *o* and rosettes *r*, the whole arranged substantially as herein shown and specified.

CHARLES DOWLER.
